UNITED STATES PATENT OFFICE.

VICTOR SCHLEYER, OF ANDERSON, INDIANA, ASSIGNOR TO MIDWEST ENGINE COMPANY, OF INDIANAPOLIS, INDIANA, A CORPORATION OF INDIANA.

SELF-MAINTAINING LUBRICATING SYSTEM FOR DEEP-WELL PUMPS.

1,392,226.

Specification of Letters Patent. Patented Sept. 27, 1921.

Application filed November 8, 1920. Serial No. 422,493.

To all whom it may concern:

Be it known that I, VICTOR SCHLEYER, a citizen of the United States, residing at Anderson, in the county of Madison and State of Indiana, have invented a new and useful Self-Maintaining Lubricating System for Deep-Well Pumps, of which the following is a specification.

It is the object of my invention to provide an effective lubricating system for deep-well pumps, where filtered water is used as the lubricant and unfiltered water and the sand and dirt which it carries in the well are kept away from the bearings, and to maintain the supply of filtered water regardless of the leakage thereof which may occur and which in the preferred form of my invention I provide for in order effectively to prevent ingress of unfiltered water at the pump bearings.

The accompanying drawing illustrates my invention: Figure 1 is a vertical central section through the upper end of a deep-well pump embodying my invention; Fig. 2 is a transverse section through such upper end; and Figs. 3 and 4 are vertical central sections through two embodiments of my invention which may be provided at the lower end of the well.

The pump casing 10 at the bottom of the well has a bottom inlet 11 and a top discharge 12, which latter opens to an upwardly extending discharge pipe 13 which leads upward through the well to a discharge fitting 14 at the top of the well. Within the pump casing 10 is a runner 15, of any convenient type, the pump being shown as having only a single runner though obviously it may have any desired number of runners. The pump runner (or runners) is mounted on a vertical shaft 16, which extends up axially through the pipes 12 and 13 and is driven in any suitable manner by a driving means at the top. Above the runner 15 a bearing 17 is provided for the vertical shaft 16, such bearing being suitably supported so that it does not interfere with the upward flow of water discharged from such runner, and such bearing 17 has a flaring upper end 18 on which is supported the casing 19 of a small lubricant-circulating pump of which the runner 20 is fixed on the shaft 16 within such casing 19. The inlet of the runner 20 is upward, tending to suck downward through the upward extension 21 of the cas-

ing 19; and its discharge is outward into a chamber 22 provided in the casing 19. Preferably the lower end of the casing 19 is separated by a plate 23 from a chamber 24 formed in the flaring upper end 18 of the bearing 17, which plate is provided with a gland 25 around the shaft 16, or around a bushing on said shaft if that is preferred; and the discharge chamber 22 is connected to the chamber 24, as by a pipe 26, to supply liquid to the chamber 24 under pressure from the runner 20 and thus the lubricant is forced downward through the bearing 17 against any tendency of unfiltered water to rise through such bearing. The chamber 22 may be connected to any other parts to be lubricated, if desired, in addition to or in place of the bearing 17, for simplicity being shown connected to that particular bearing.

The upward extension 21 of the casing 19 is connected to the lower end of a lubricant-conducting pipe 30 which surrounds the shaft 16 and extends upward from such extension 21 through the discharge fitting 14, as is clear from Fig. 1. The shaft 16 may be provided with any suitable bearings 31 at desired points, such bearings being within the pipe 30. Near its upper end, preferably above the topmost bearing 31, the pipe 30 is connected by a supply pipe 32 to the inner part of a settling tank 33, which is provided in the pump head 34 with which the intake fitting 14 is integral. This settling tank is provided with a plurality of curved baffles 35 opening alternately at opposite ends, to provide a plurality of spaces 36 which together constitute a serpentine settling passageway leading to the pipe 32, which is connected to the inner space 36, preferably at a point considerably above the bottom thereof. The outer space 36 is connected to the upper end of a return pipe 37 which extends down into the well beside the pipe 30 and is connected at its lower end to the discharge chamber 22 of the lubricant-circulating pump. The settling tank is provided with a filling and overflow pipe 38, which leads into the outer space 36.

When the device is in operation, the runner 20 draws the lubricating water from the inside space 36 of the tank 33, through the pipe 32 and down through the pipe 30 to lubricate the bearings 31, and discharges such lubricating water into the discharge chamber 22, whence the water is in part re-

turned by the pipe 37 to the outer space 36 of the settling tank and in part discharged through the pipe 26 through the bearings 17 or other pump parts to be lubricated. In order to supply the loss of lubricating water, especially on account of the outflow through the bearing 17, I provide one or more water inlet openings 40 through the upward extension 21 of the casing 19 for admitting water from the well, which openings 40 communicate either directly with the space within the water-discharge pipe 12 of the main water pump, by way of filters 41, as shown in Fig. 3, or by way of a pipe 42 having a filter 43 at its outer end with the space within the well outside of the pump casing and discharge pipe, as shown in Fig. 4. The passage 40 provides a water inlet directly to the intake of the runner 20 of the lubricant-circulating pump, and the filters 41 or 43 effectively strain such water and prevent ingress of dirt or sand. The filling and overflow pipe 38 permits the proper level to be maintained in the tank 33, either by allowing any excess to overflow in case more water is drawn through the openings 40 than is lost or by permitting additional water to be poured into such tank, which is preferably provided with a water level gage 44 for indicating the water level. In case any sand or dirt is carried in through the openings 40, it is taken directly by the runner 20 without first passing through any of the bearings 31, and if carried up through the pipe 37 into the tank 33 is there permitted to settle out of the water as the latter travels through its serpentine course toward the pipe 32, so that the water finally supplied to such pipe 32 and therethrough to the pipe 30 will be substantially free from sand and dirt.

The inflow of water through the openings 40, primarily produced by the suction of the lubricant-circulating pump, may be augmented by an injector action from the downwardly flowing main stream to such pump, as by giving the openings 40 a component of discharge in the direction of such stream flow to produce a sucking Pitot-tube action and by making the inner wall of the extension 21 in the general form of a Venturi tube into which the openings 40 communicate at about the beginning of the expanding portion thereof.

I claim as my invention:

1. In a deep-well pump, the combination of a shaft extending down into the well, a rotary pump in the well and having a runner connected to said shaft, a water-discharge pipe extending up from said pump around said shaft, a lubricant pump also located in the well and having a runner connected to said shaft, a lubricant-conducting pipe surrounding said shaft and extending upward from the inlet of said lubricant

pump, a tank connected to the upper end of said lubricant-conducting pipe, a second lubricant-conducting pipe extending upward from the discharge of said lubricant-pump to said tank, said tank being arranged to provide a serpentine course between said two pipes to permit settling from the lubricant of any sand and dirt carried thereby, and a water-admission conduit provided with a filter and connecting the inlet of said lubricant pump with the water in the well. 75

2. In a deep-well pump, the combination of a shaft extending down into the well, a rotary pump in the well and having a runner connected to said shaft, a water-discharge pipe extending up from said pump, a lubricant pump also located in the well and having a runner connected to said shaft, a lubricant-conducting pipe surrounding said shaft and extending upward from the inlet of said lubricant pump, a tank connected to the upper end of said lubricant-conducting pipe, a second lubricant-conducting pipe extending upward from the discharge of said lubricant-pump to said tank, said tank being arranged to provide a serpentine course between said two pipes to permit settling from the lubricant of any sand and dirt carried thereby, and a water-admission conduit provided with a filter and connecting the inlet of said lubricant pump with the water in the well. 90

3. In a deep-well pump, the combination of a shaft extending down into the well, a rotary pump in the well and having a runner connected to said shaft, a water-discharge pipe extending up from said pump around said shaft, a lubricant pump also located in the well and having a runner connected to said shaft, a lubricant-conducting pipe surrounding said shaft and extending upward from the inlet of said lubricant pump, a tank connected to the upper end of said lubricant-conducting pipe, a second lubricant-conducting pipe extending upward from the discharge of said lubricant-pump to said tank, and a water-admission conduit provided with a filter and connecting the inlet of said lubricant pump with the water in the well. 105

4. In a deep-well pump, the combination of a shaft extending down into the well, a rotary pump in the well and having a runner connected to said shaft, a water-discharge pipe extending up from said pump, a lubricant pump also located in the well and having a runner connected to said shaft, a lubricant-conducting pipe surrounding said shaft and extending upward from the inlet of said lubricant pump, a tank connected to the upper end of said lubricant-conducting pipe, a second lubricant-conducting pipe extending upward from the discharge of said lubricant-pump to said tank, and a water-admission conduit provided with a filter and connecting the inlet of said lubricant pump with the water in the well. 110

5. In a deep-well pump, the combination of a shaft extending down into the well, a rotary pump in the well and having a runner connected to said shaft, a water-discharge pipe extending up from said pump around said shaft, a lubricant pump also located in the well and having a runner connected to said shaft, a lubricant-conducting pipe surrounding said shaft and extending upward from the inlet of said lubricant

and connecting the inlet of said lubricant pump with the water in the well.

5. In a deep-well pump, the combination of a shaft extending down into the well, a 5 rotary pump in the well and having a runner connected to said shaft, a water-discharge pipe extending up from said pump, a lubricant pump also located in the well and having a runner connected to said shaft, 10 a lubricant-conducting pipe surrounding said shaft and extending upward from the inlet of said lubricant pump, a tank connected to the upper end of said lubricant-conducting pipe, a second lubricant-conducting pipe extending upward from the discharge of said lubricant-pump to said tank, and a water-admission conduit provided with a filter and connecting the inlet of said lubricant pump with the water in the well 15 within said water-discharge pipe.

6. In a deep-well pump, the combination of a shaft extending down into the well, a rotary pump in the well and having a runner connected to said shaft, a water-discharge pipe extending up from said pump, a lubricant pump also located in the well and having a runner connected to said shaft, a lubricant-conducting pipe surrounding said shaft and extending upward from the inlet 20 of said lubricant pump, a tank connected to the upper end of said lubricant-conducting pipe, a second lubricant-conducting pipe extending upward from the discharge of said lubricant-pump to said tank, a water-admission conduit provided with a filter and connecting the inlet of said lubricant pump with the water in the well, a bearing for said shaft, and a connection from said bearing to the discharge of said lubricant pump 25 so that lubricant is supplied to said bearing under pressure.

7. In a deep-well pump, the combination of a shaft extending down into the well, a rotary pump in the well and having a runner connected to said shaft, a water-discharge pipe extending up from said pump, a lubricant pump also located in the well and having a runner connected to said shaft, a lubricant-conducting pipe surrounding said shaft and extending upward from the inlet 30 of said lubricant pump, a tank connected to the upper end of said lubricant-conducting pipe, a second lubricant-conducting pipe extending upward from the discharge of said lubricant-pump to said tank, a water-admission conduit provided with a filter and connecting the inlet of said lubricant pump with the water in the well, a main pump bearing for said shaft between said two runners, and a connection from the discharge of said lubricant pump to one end of said bearing.

8. In a deep-well pump, the combination of a shaft extending down into the well, a 65 rotary pump in the well and having a runner

fixed on said shaft, a water-discharge pipe extending up from said pump, a lubricant pump also located in the well and having a runner fixed on said shaft above the main pump runner, a lubricant-conducting pipe surrounding said shaft and extending upward from the inlet of said lubricant pump, a second lubricant-conducting pipe extending upward from the discharge of said lubricant-pump, and a water-admission conduit provided with a filter and connecting the inlet of said lubricant pump with the water in the well.

9. In a deep-well pump, the combination of a shaft extending down into the well, a 80 rotary pump in the well and having a runner fixed on said shaft, a water-discharge pipe extending up from said pump around said shaft, a lubricant pump also located in the well and having a runner fixed on said 85 shaft above the main pump runner, a lubricant-conducting pipe surrounding said shaft and extending upward from the inlet of said lubricant pump, a second lubricant-conducting pipe extending upward from the discharge of said lubricant-pump, and a water-admission conduit provided with a filter and connecting the inlet of said lubricant pump with the water in the well.

10. In a deep-well pump, the combination of a shaft extending down into the well, a rotary pump in the well and having a runner connected to said shaft, a water-discharge pipe extending up from said pump, a lubricant pump also located in the well 95 and having a runner connected to said shaft, a lubricant-conducting pipe surrounding said shaft and extending upward from the inlet of said lubricant pump, a second lubricant-conducting pipe extending upward from the discharge of said lubricant-pump, and a water-admission conduit provided with a filter and connecting the inlet of said lubricant pump with the water in the well.

11. In a deep-well pump, the combination of a shaft extending down into the well, a rotary pump in the well and having a runner connected to said shaft, a water-discharge pipe extending up from said pump, a lubricant pump also located in the well and having a runner connected to said shaft, a lubricant-conducting pipe surrounding said shaft and extending upward from the inlet of said lubricant pump, a second lubricant-conducting pipe extending upward from the discharge of said lubricant-pump, and a water-admission conduit provided with a filter and connecting the inlet of said lubricant pump with the water in the well, the discharge end of said water-admission conduit being so associated with said lubricant-conducting pipe that it is given a sucking Pitot tube action from the liquid flow through such pipe.

12. In a deep-well pump, the combination 130

of a shaft extending down into the well, a
5 rotary pump in the well and having a runner
connected to said shaft, a water-dis-
charge pipe extending up from said pump,
a lubricant pump also located in the well
and having a runner connected to said shaft,
10 a lubricant-conducting pipe surrounding
said shaft and extending upward from the
inlet of said lubricant pump, a second lubri-
cant-conducting pipe extending upward
from the discharge of said lubricant-pump,
and a water-admission conduit provided with
a filter and connecting the inlet of said lubri-
cант pump with the water in the well, said
water-admission conduit and said lubricant- 15
conducting pipe being associated to produce
an injector action on the former from the
liquid flow through the latter.

In witness whereof I have hereunto set my
hand at Anderson, Indiana, this 26th day 20
of October, A. D. one thousand nine hundred
and twenty.

VICTOR SCHLEYER
